ELECTRIC VACUUM CLEANER BODY

Paul O. Rawson, Jr., Easton, and Bruno M. Valbona and John J. Hamilton, Avon, Conn., assignors to Dynamics Corporation of America, New York, N.Y.

Filed Mar. 9, 1970, Ser. No. 21,780

Term of patent 14 years

Int. Cl. D15—07

U.S. Cl. D49—13

FIG. 1

FIG. 2

FIG. 3

FIG. 1 is a side elevational view of an electric vacuum cleaner body showing our new design the side opposite being similar in appearance.

FIG. 2 is a perspective view thereof from below and behind; and

FIG. 3 is a perspective view thereof from in front and above.

We claim:

The ornamental design for an electric vacuum cleaner body, as shown and described.
